(57) **CLAIM**

The ornamental design for a bottle, as shown and described.

DESCRIPTION

FIG. 1 is a front perspective view of a bottle showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a cross-sectional view thereof taken along line 7-7 of FIG. 2;

FIG. 8 is a cross-sectional view thereof taken along line 8-8 of FIG. 2; and,

FIG. 9 is a bottom view thereof.

The broken lines in the drawings depict environmental subject matter only and form no part of the claimed design. The hatched lines in the drawings depict environmental subject matter only and form no part of the claimed design.

1 Claim, 8 Drawing Sheets
